UNITED STATES PATENT OFFICE.

EDWARD WALKER, OF GRANTWOOD, NEW JERSEY.

DISHWASHING APPARATUS.

Application filed September 22, 1924. Serial No. 739,082.

To all whom it may concern:

Be it known that I, EDWARD WALKER, citizen of the United States, residing at Grantwood, in the county of Bergen and State of 5 New Jersey, have invented certain new and useful Improvements in Dishwashing Apparatus, of which the following is a specification.

My invention relates to an apparatus and 10 method for the washing of various household articles and is especially adapted for the washing of dishes.

The invention has for its object to provide a method whereby water may be 15 trained in an air current in the form of a spray which spray may be properly applied to the articles to be cleaned.

It also has for its object to provide mechanical means which will serve to deviate 20 the escaping current outwards and direct it against the articles to be washed.

My invention further has for an object to furnish rotating air outlet nozzles which 25 rotating nozzles will serve to discharge the spray successively in all directions thus making an efficient spray adapted to reach all the articles to be washed.

Further my invention has for its object 30 to provide a bottom which slants downwards and towards the air discharge which will in combination with a downward directed air current cause the water to travel upwards away from the air discharge in consecutive waves the crests of which are 35 broken up in a spray by the air current.

Finally my invention provides for the 40 placing of the dishes edgewise around the air discharge in a fan like arrangement so that the space between the dishes will increase with the distance from the air discharge where the spray action naturally is decreased.

In the drawing:—

Figures 1 and 2 show in a diagrammatical way the washing of dishes and tableware.

Figure 3 is a horizontal section of the 50 dish washer showing the eccentric fan like arrangement whereby different size plates can be accommodated with the least loss of space.

Figures 4, 5, and 6 show different types of air discharge nozzles.

Of these nozzles Figure 4 shows a stationary type supplied with a conical deflector.

Figure 5 shows a nozzle type adapted to rotate in the space below the supporting dish shelf.

Figure 6 shows a nozzle provided with a 60 fan adapted to rotate in the spray below the supporting dish shelf.

Referring to the drawing in which like reference characters designate corresponding parts, 1 designates a washer which is 65 adapted to wash dishes and table ware.

The dish washer shown has one lower part 2 adapted to retain water and an upper part or cover 3 which fits tight on the lower 70 part.

On top of the cover an electrically driven fan 4, is mounted.

The fan intake 5 is supplied with a water separator 6 which prevents the sucking of 75 water through the fan.

The bottom part 2 of the washer has the 80 bottom slanting towards the air discharge and the bottom is also supplied with a cup like depression 7 directly below the air discharge into which depression the water will continuously flow back during the washing operation.

A shelf 8 is shown supporting the plates 10, saucers 10' and articles of tableware 10'.

The air discharge pipe 11 is connected at 85 its upper end to the fan 4 and receives therefrom a blast of air sufficient to agitate the water in the bottom of the washer, said pipe being provided close to its end with a conically shaped deflector 12 which aids in spraying the water that is agitated by the blast of air from the pipe 11.

Figure 5 shows the detail construction of 90 a rotating nozzle the air discharge taking place downwards through the opening 13 as well as laterally through the side openings 14 which direct the discharge so as to cause the nozzle to rotate in the ball bearing 15 which is provided on the air discharge.

The Figure 6 shows a nozzle 16 provided 95 with a rotating fan 17 which is also suspended on a ball bearing 15' and rotated by means of vanes 18 which are placed inside the air discharge.

The mode of procedure is as follows.

After the articles to be cleaned have been 100 properly placed and an amount of hot water just in excess of the capacity of the cup like depression has been poured into the bottom part 2, the washer is closed and the fan 4 is started.

The lower end of the air discharge pipe 110

11 is immersed to the depth of about one inch in the water so that when said water is agitated the end of said pipe will be above said surface and thus the maximum spray and swash effect will take place.

It is also to be noted that the shape of the bottom of the washer does cause the water agitated by the impact of the air discharge to swash back and forth forming waves from the crests of which waves a spray is blown by the air current.

The cone shaped deflector with which the air discharge is provided forms together with the water itself and the slanting bottom of the washer a passage way through which the air current must escape outwards and it is plain that the narrower this passage way becomes, the greater the air velocity and also the spray action.

Therefore it is of importance to place the air discharge at such a distance above the water surface that the maximum spray will occur.

I do not desire to be understood as limiting myself to the specific details of construction and arrangement as it is manifest that variations and modifications may be made in the adaptations of the device to various conditions, without departing from the spirit and scope of my invention.

I claim:—

1. The herein described machine for washing dishes, including a receptacle for water, means for blowing air against the surface of the water so as to agitate the water in waves, and means for supporting dishes above and around the air discharge, the water being blown in a spray between the dishes.

2. The herein described machine for washing dishes, including a receptacle for water, means for blowing air against the surface of the water and causing a spray, a dish support, and means for deflecting the spray between the dishes.

EDWARD WALKER.
